UNITED STATES PATENT OFFICE.

ERNEST M. SIMS, OF ELKHART, INDIANA, ASSIGNOR TO METAL FORMING CORPORATION, OF ELKHART, INDIANA, A CORPORATION OF INDIANA.

TEXTILE-BOBBIN.

1,368,991.

Specification of Letters Patent. Patented Feb. 15, 1921.

Application filed April 5, 1919. Serial No. 287,746.

To all whom it may concern:

Be it known that I, ERNEST M. SIMS, a citizen of the United States, residing at Elkhart, county of Elkhart, and State of Indiana, have invented certain new and useful Improvements in Textile-Bobbins, of which the following is a specification.

The invention relates to improvements in textile bobbins, and aims to produce as a new article of manufacture a textile bobbin made of metal as distinguished from the ordinary wooden bobbins which are in general use in textile establishments for the storage of yarns and the like.

While the initial cost of wooden bobbins may be relatively low, it is to be noted that the upkeep of the same is comparatively high. They break very frequently when roughly handled, and if broken are entirely useless. They also have the peculiarity of absorbing oils or other liquids, and while not excessive in weight, must be made rather clumsy in order to provide for sufficient strength and stiffness. It is also a disadvantage of wooden bobbins that they are inflammable and that their weight is far from being uniform, consequently it is difficult to ascertain with exactness the weight of the yarn stored on the bobbin.

It is an object of the present invention to manufacture a bobbin in which these disadvantages are avoided. The metal bobbins can not only be made at a low initial cost, but they also require only a very small additional expenditure for the upkeep.

It is furthermore an object to provide a bobbin which does not break as easily as a wooden bobbin, which has smoother edges than the ordinary wooden bobbin, and which therefore does not readily catch the strands of yarn to be stored on the bobbin.

It is furthermore an object of the invention to construct a bobbin having flange plates which when bent can easily be restored to their original condition or which can be replaced, thereby eliminating the great waste which could not be avoided in the use of wooden bobbins.

It is also an object of this invention to provide a metal bobbin which with the same diameter of flange plate will permit the use of a smaller barrel without decrease in the strength or stiffness of the bobbin, so that on a metal bobbin of this size a greater

amount of yarn can be wound than on a wooden bobbin.

It is furthermore an object of the invention to provide a metal bobbin of this character with driving lugs which may be readily replaced whenever they become worn or damaged, and which facilitate the counterbalancing of the two flange plates of the bobbin.

It is obvious also that in metal bobbins greater uniformity of weight is attainable when these bobbins are made on a large scale, and that the dangers of combustion of the bobbins are avoided.

With these and other objects in view, the invention is described in the following specification, reference being had to the accompanying drawing, wherein:

Figure 1 is a perspective view of a metal bobbin of this kind;

Fig. 2 is a vertical central section through a portion of a barrel and a flange plate;

Fig. 3 is a sectional view of one of the spokes of the flange plate;

Fig. 4 is a sectional view of a brace connected with the flange plate, and

Fig. 5 illustrates a front elevation of a modified flange plate.

The bobbin comprises a barrel 1 and flange plates 2, secured to the barrel near the ends thereof and in planes at right angles to the axis of the barrel. The barrel is formed, as may be seen from Figs. 1 and 2, as a tubular member having near its ends wooden bearing plugs 3, inserted in the barrel and held therein by pins or the like. It is obvious that these wooden bearings can readily be exchanged at small expense when they become worn.

For the purpose of increasing the strength of the flange plates, the latter are provided with reinforcing portions which extend in the form of a bead 4 along the circumferential edge of the flange plate 2, and also with spokes 5, which connect the marginal portions of the flange plates with the central portion of the same. From Fig. 3 it will be noticed that the metal spokes 5 are reinforced by bending the same longitudinally, providing a radial curvature 6 and longitudinal marginal bends 7. The beads 4 of the flange plates are turned outwardly, leaving the entire space between the two flange plates free for the storage of yarn or

like material, and owing to the rounded bead, the danger of catching thread or yarn on the circumference of the flange plates is eliminated.

5 For further strengthening the flange plates 2 the latter are provided, in alternation with the spokes 5, with braces 8, which also are preferably made integral with the flange plates, and which extend angularly 10 from the planes defined by the spokes 5 of the plates. The inner ends of these braces 8 are shaped into hook form, as indicated at 9, and the hooks are inserted into slots 10 of hub disks 11, which are fixed to the outer 15 ends of the barrels 1 of the bobbin. From Fig. 2 it will be noted that the hub disks are made of stock which is heavier than the stock of the barrel or flange plates, and these hub disks are inserted by means of 20 their shoulder portions 12 between cylindrical extensions 13 of the flange plates and between angular marginal portions 14 at the ends of the barrels 1. The main portion of the braces 8, which are also made integral 25 with the flange plates, is bent into circular shape, as shown in Fig. 4, to strengthen the entire structure.

Driving lugs 15, in the form of bell-shaped strips, are secured at their outer ends 30 to the marginal portions of the flange plates at 16, while their inner or raised ends are connected to the marginal portions of the hub disk 11 by means of rivets 17 or the like. These driving lugs are provided with 35 suitable openings 18, into which the driving member of the spinning machine or the like may be inserted. While, according to Fig. 1, each of the flange plates has a single driving lug 15, the modified end flange shown 40 in Fig. 5 illustrates an arrangement wherein two of these driving lugs 15 are provided on the same face of the flange plate. From Fig. 1 it will also have to be noted that the two flange plates at the ends of the bobbin 45 are angularly offset with respect to each other, so that axial planes placed centrally through the spokes and braces of one flange plate will pass centrally through the braces and spokes respectively of the other flange 50 plate. In this manner the entire weight of the flange plates is uniformly distributed over the bobbin structure, and the exact balance which is necessary in the high speed rotation of these implements is carefully 55 maintained. This maintenance may be enhanced by the provision of two driving lugs diametrically opposite each other in each flange plate; the driving lugs on one flange plate, however, being offset angularly with 60 respect to the driving lugs of the other flange plate, as indicated in Fig. 5.

I claim:

1. As an article of manufacture, a textile bobbin, comprising a barrel, hub disks at

the ends of the barrel, flange plates secured 65 to the barrel, and braces secured to said flange plates and connected with said hub disks.

2. As an article of manufacture, a textile bobbin, comprising a metal barrel, hub disks 70 at the ends of the barrel, flange plates on said barrel intermediate said disks, and braces, the hub disks being provided with slots and the braces having terminal hook portions entering said slots. 75

3. As an article of manufacture, a textile bobbin, comprising a tubular metal barrel having marginal angular portions, flange plates provided with a cylindrical flange portion seated on said barrel, hub disks secured to said barrel between said marginal angular portion and said cylindrical flange portion and elements connecting said flange plates and hub disks. 80

4. As an article of manufacture, a textile 85 bobbin, comprising a barrel and metal end flange plates having spokes alternating with braces, the spokes and braces in one flange plate being angularly offset with respect to the spokes and braces in the other flange 90 plate.

5. As an article of manufacture, a textile bobbin, comprising a barrel and metal end flange plates having spokes alternating with braces, the flange plates being so disposed 95 with respect to each other that axial planes placed centrally through the spokes and braces of one flange plate pass centrally through the braces and spokes respectively of the other flange plate. 100

6. A textile bobbin, comprising a metal barrel having marginal angular portions, flange plates consisting of radial arms and a beaded rim seated on said barrel, hub disks of heavier stock than the flange plates 105 mounted on the ends of the barrel, said flange plates being provided with brace members which enter slots in said hub disks.

7. A textile bobbin, comprising a metal barrel having marginal angular portions, 110 flange plates provided with a cylindrical flange portion seated on said barrel, said flange plates being provided with integral radial arms extending from the cylindrical portion to the circumferential portion of the 115 plate and being provided with braces integral with the marginal portion of the flange plate, hub disks having a cylindrical flange engaging the barrel and of heavier stock than the barrel and the flange plate, the inner ends 120 of the braces being removably connected with the hub disks.

In testimony whereof I affix my signature in the presence of two witnesses.

ERNEST M. SIMS.
